227,903

ADAPTER FOR A CIRCUIT BREAKER

Ronald Nicol, 316 McAdoo Ave., Trenton, N.J. 08619

Continuation-in-part of design application Ser. No. 21,039, Jan. 22, 1970. This application July 1, 1971, Ser. No. 159,104

Term of patent 14 years

Int. Cl. D26—03

U.S. Cl. D26—13

Fig. 11.

FIG. 1 is a side elevational view of an adapter for a circuit breaker, the other side (not shown) of the adapter being substantially the same;

FIG. 2 is a front view thereof;

FIG. 3 is a bottom view thereof;

FIG. 4 is a top view thereof;

FIGS. 5, 6, 7 and 8 illustrate a modification of my invention wherein FIG. 5 is a side elevational view of the adapter for a circuit breaker, but showing the side of the circuit breaker opposite from that shown in FIG. 1, the other side (not shown) of the adapter being substantially the same;

FIG. 6 is a front view of the adapter shown in FIG. 5;

FIG. 7 is a bottom view of the adapter shown in FIG. 5;

FIG. 8 is a top view of the adapter shown in FIG. 5;

FIGS. 9, 10, 11 and 12 illustrate a further modification of my invention wherein FIG. 9 is a side elevational view of the adapter for a circuit breaker, but showing the same side of the circuit breaker as that shown in FIG. 1, the other side (not shown) of the adapter being substantially the same;

FIG. 10 is a front view of the adapter shown in FIG. 9;

FIG. 11 is a bottom view of the adapter shown in FIG. 9;

FIG. 12 is a top view of the adapter shown in FIG. 9;

The portions of the figures shown in broken lines are shown for illustrative purposes only.

This is a continuation-in-part of design application Ser. No. D. 21,039, filed Jan. 22, 1970 Pat. No. 223,119, Mar. 28, 1972.

I claim:

The ornamental design for an adapter for a circuit breaker, as shown and described.
